FACSIMILE APPARATUS

Albert Blain, Philadelphia, Pa., assignor to Radio Corporation of America, a corporation of Delaware

Application October 31, 1942, Serial No. 464,094

20 Claims. (Cl. 173—7.1)

This invention relates to an improvement in facsimile transmitters or duplicators.

In facsimile transmitting apparatus, it is necessary to scan the copy in bi-dimensional directions in order to produce picture signals which may be transmitted to a remotely located facsimile receiving station, or which may be amplified and supplied directly to the recorder of a facsimile reproducer. The bi-dimensional scanning is normally produced by positioning the material to be scanned on a rotating drum and by directing a light beam against the periphery of the drum so that the reflected light may be received by a light responsive cell to produce the facsimile picture signals. Each rotation of the drum produces, in effect, a line scanning operation, and simultaneously with the rotation of the drum, the scanner head (which normally includes at least the light source and the photocell) is moved longitudinally with respect to the drum to produce, in effect, the scanning action in the opposite direction, i. e., in the direction normal to the lines. In some modifications, however, the material to be scanned is positioned in a stationary support arrangement, and a rotating and longitudinally movable scanner head is used to produce the bi-dimensional scanning action. An example of such an arrangement is shown and described in Young Patent No. 2,298,911, issued October 13, 1942, and in Schroter et al. Patent No. 1,746,407, issued February 11, 1930.

In facsimile duplicators, it is frequently desirable to have a plurality of facsimile copies made from a single original, and, furthermore, the size of the original may vary considerably in length. The present invention is, therefore, particularly concerned with the scanning mechanism used in a facsimile transmitter or duplicator whereby it is possible to produce bi-dimensional scanning, and whereby it is possible to repeat the scanning action a predetermined number of times. Furthermore, the present invention is concerned with adjustable means whereby the length of travel of the scanner head may be conveniently pre-set so that adjustments may be made to compensate for different lengths of material.

Naturally, the longitudinal movement of the scanner head is relatively slow, and after one complete scanning operation has been performed, it is necessary to return the scanner head to its initial starting position. In order to avoid loss of time, it is desirable that the scanner head be returned to the initial starting position in a minimum length of time, and that the subsequent

scanning of the material be begun automatically.

The present invention also relates to the provision of means whereby the transmitter may be set to scan the material any desired number of times, and to count the successive scanning operations as they are performed. Furthermore, the present invention also relates to the provision of means for automatically discontinuing the scanning action after the desired number of copies has been made, or after the desired number of scanning operations has been performed.

The design of the present invention is, therefore, particularly adaptable for use in facsimile duplicators where a facsimile reproducer is directly associated with the scanner or transmitter, so that a plurality of facsimile copies of the original may be produced. By using present high speed facsimile principles and the feature of the present invention, it is, therefore, possible to make a relatively large number of completely finished facsimile copies in a relatively short length of time, especially where an electrolytic recording process is used.

One purpose of the present invention is, therefore, the provision of means in a facsimile transmitter or duplicator, whereby a bi-dimensional scanning operation may be performed in a minimum length of time together with the provision of means whereby the scanner head may be automatically returned to the initial starting position at the conclusion of the scanning operation.

Another purpose of the present invention resides in the provision of means whereby the length of travel of the scanner head may be made adjustable so that the scanning operation will continue for a predetermined length of time or distance along the material to be scanned, and after the predetermined distance has been scanned, the scanner head will automatically return to its initial starting position.

A still further purpose of the present invention resides in the provision of means whereby the facsimile transmitter may be caused to scan the original material a predetermined adjustable number of times without any action on the part of the operator, and with a minimum of lost time or motion.

Still another purpose of the present invention resides in the provision of means in a facsimile transmitter or duplicator whereby the scanning operation may be completely discontinued after the desired number of scanning operations has been performed.

A still further purpose of the present invention resides in the provision of means in a facsimile

transmitter or duplicator whereby the scanner head may be returned to its initial starting position in a minimum length of time, and whereby the apparatus may be protected from injury or damage due to the relatively quick return of the scanner head.

Still other purposes and advantages of the present invention will become more apparent to those skilled in the art from the following detailed description, particularly when considered in connection with the drawings, wherein like reference numerals represent like parts, and where-

Figure 1 shows a perspective view of a preferred form of a facsimile duplicator;

Figure 2 shows in detail the construction and relationship of various elements of the transmitter, Figure 2 being a section approximately along section lines 2-2 of Figure 1;

Figure 3 shows a detailed plan view of a portion of the mechanism taken approximately along section lines 3-3 of Figure 2;

Figure 4 shows a detailed plan view of a portion of the mechanism taken approximately along section lines 4-4 of Figure 2;

Figure 5 is a detailed showing approximately along section lines 5-5 of Figure 2, and shows the wind vane governor;

Figure 6 is a plan view partially in section showing the scanner head and the drive mechanism therefor; and

Figure 7 is a detailed view taken approximately along section lines 7-7 of Figure 6.

Referring now to Figure 1, there is shown a perspective view of a preferred form of a facsimile duplicator. In this particular apparatus, the picture signals produced as a result of the scanning operation are amplified and are supplied by direct wire connection to the recording electrodes of the recording mechanism associated with the scanning mechanism. Since the scanner and the recorder are adjacent each other, and since it is possible to rotate the scanning drum and the recording drum by the same driving motor, no synchronizing signals are necessary since synchronous operation between the transmitter and the receiver is assured by reason of a direct mechanical connection. It is, however, necessary to maintain proper phase relationship, and the provision for maintaining this relationship will be referred to later.

In Figure 1, the driving motor is located beneath the recorder end of the duplicator, and is connected to the recording drum to which is directly coupled the scanning drum. The scanning end of the duplicator also includes a scanner head, and a mechanism for producing the desired movement of the scanner head with respect to the scanning drum. The amplifiers for amplifying the produced picture signals are not shown in Figure 1, but are located in the space beneath the scanning mechanism shown in the figure.

The scanner head is represented in general at 10, and includes a lamp housing 12 which surrounds an exciter lamp 14 which supplies the light for generating the picture signals. A lens tube 16 is associated with the lamp housing and is provided for directing and focusing the light against the surface of the material 18 to be scanned. This material is positioned on the scanning drum 20. The scanner head also includes a housing 28 which encloses a photocell or other light responsive element 30, and if desirable, one or more stages of pre-amplification may be pro-

vided by the inclusion of an amplifier tube 32. The housing 28 which encloses the photocell is naturally directly connected to the lamp housing 12 and the light tube 16. A light passage is provided between the photocell 30 and the point where the light from the source 14 is directed upon the material to be scanned. Provision is made for transporting the scanner head longitudinally along the scanner on a line parallel to the axis of the scanning drum 20. The drum is supported by a special clutch arrangement 22 and by a tail stock assembly shown generally at 24. The clutch assembly 22 is positioned on a shaft mechanically connected to the printing drum 26, which is driven by a motor or other source of power (not shown).

The transmitting or scanning end of the duplicator also includes in general the mechanism for producing the scanning action through movement of the scanner head 10.

The recorder end of the duplicator includes, in addition to the printing drum, a drive roller 34 and an ironing and drying roller 36. These last mentioned elements are driven by means of a mechanical connection between the scanning drum and the elements. The recorder also includes a cover member represented at 38 for retaining the recording paper 40 in proper cooperation with the feed roller 34 and the scanning drum 26. The cover member 38 also carries a printer bar which cooperates with the printing drum.

The recording paper 40 may be supplied from a supply roll 42, which may be impregnated with the required chemical solution, or which may be unimpregnated, in which case an immersion bath is included through which the paper is passed prior to its being directed to the recording mechanism. Inasmuch as the present invention is not concerned with the particular construction or operation of the recorder, further description of this portion of the mechanism will not be supplied. For a more detailed description of the construction of a preferred form of the recorder, attention is directed to Artzt application, Serial No. 459,137, filed September 21, 1942, and Blain application, Serial No. 460,615, filed October 3, 1942.

The particular construction of the clutch member 22, together with the tail stock arrangement 24, does not form a specific part of the present invention, and accordingly these elements will not be described in detail. Their construction, however, is such as will permit the scanning drum to be removed from the duplicator without the necessity of stopping the entire mechanism, and, furthermore, their construction is such as will permit a drum to be reinstalled in the machine, to be brought up to proper rotational speed, and positioned in proper phase relationship or orientation with respect to the printing drum 26 without disturbing the remainder of the duplicator. Specific details of the particular clutch arrangement and tail stock assembly are shown and described in Artzt application, Serial No. 456,000, filed August 25, 1942.

A perspective view of the mechanical arrangement for causing movement of the scanner head and for returning the scanner head to an initial position is shown in Figure 1. However, in view of the fact that not all of the elements are visible in Figure 1, this particular mechanism is shown more clearly in detail in Figure 2, as well as parts thereof in other figures. Figure 2 is a section through the duplicator taken approxi-

mately along section lines 2—2 shown in Figure 1.

Referring now to Figure 2, one wall 44 of the recorder is shown, behind which is positioned the scanning drum 28, the feed roller 34 and the ironing and drying roller 36. As previously stated, the scanning drum 28 is driven by any appropriate source of motive power. The shaft of the printing drum extends through the wall 44 and carries the clutch mechanism 22, as best indicated in Figure 1. Between the scanning drum and the clutch assembly 22 is a worm and gear assembly 46 for rotating a counter-shaft 48 at a relatively slow rate of speed. The counter-shaft 48 is provided with a worm and gear assembly 50 for rotating the ironing and drying roller 36, and the opposite end of the counter-shaft is provided with a worm 52 with which cooperates a worm gear 54 connected to the feed roller 34. The same worm 52 also cooperates with a worm gear 56, and this gear is rigidly secured to the vertical shaft 58, by means of pin 60. As the printing drum is rotated, the scanning drum, when in engagement with the clutch mechanism 22 as shown in Figure 1, is also rotated at the same speed, and, by means of the counter-shaft 48, the feed roller operates to supply the recording paper to the recording mechanism. Simultaneously, the gear 56 together with its shaft 58 are rotated at a relatively slow rate of speed. The shaft 58 is retained in position by means of two bearings 62 and 64, the bearings being carried by parallel support plates 66 and 68 respectively. These two support plates are joined by a spacer member 70 in order to assure a rigid connection.

The vertical shaft 58 also carries a ratchet wheel 72, which is permanently secured to the shaft 58 by means of the sleeve 74 and pin 76.

A cable drum 78 is positioned on the shaft 58, and is permitted to rotate with respect thereto. The cable drum 78 also carries a gear 80, the gear being attached to the cable drum by means of rivets or other appropriate securing means.

The gear 80 cooperates with a smaller gear 82 which is mounted on shaft 84, the shaft being supported by the lower support plate 66. The opposite end of the shaft 84 is provided with a gear 86 which is arranged to cooperate with a smaller gear 88, the latter being positioned on shaft 90, one end of the shaft 90 being carried by the lower plate 66 and the opposite end of the shaft 90 being supported by the adjustable needle bearing member 92. The adjustable needle bearing is supported by the lower support plate 66 by means of the bracket 94. The shaft 90 is also provided with a plurality of wind vanes 96, the purpose of which will be described later. The gear 88 is not directly secured to the shaft 84, but instead, a one-way clutch or "free-wheeling" connection is provided. A mechanical connection is provided between the shaft 84 and the gear 86 by means of the coiled coupling spring 98. One end of the coupling spring is attached to or permitted to engage a pin near the periphery of the gear 86 and the coiled portion of the spring is dimensioned to fit snugly about the shaft 84. The other end of the coupling spring is left free. The spring is held in place by means of a collar positioned on the end of the shaft 84. The purpose of this coupling spring or "free-wheeling" unit will become more apparent when the operation of the mechanism is described.

The cable drum 78 and gear 80 are rotated in one direction by means of the shaft 58 through the ratchet 72 and a cooperating pawl member

100, best shown in Figure 4. The pawl is attached to the cable drum 78, and is pivoted thereon by means of a rivet or other appropriate securing means 102. When the pawl is in one position, 5 it causes a mechanical engagement between the ratchet 72 and the cable drum 78, whereas when the pawl is in the other position, these elements are disengaged and no driving action is provided. The pawl 100 is provided with a toggle spring 104, one end of which is connected to the pawl and the other end of which is connected to the cable drum 78. The location of the ends of the toggle spring 104 with respect to the pivot point 102 is such as will cause the pawl to be retained 15 in the engaged or disengaged position with respect to the ratchet wheel 72.

When the pawl is in engagement with the ratchet wheel 72, the cable drum 78 and the gear 80 are rotated by the shaft 58 in the direction indicated by the arrows in Figure 4. This rotation causes a spring 106 (see Figure 2) to be stressed in order to store energy in the spring. The spring is located immediately below the gear 80, and one end of the spring is attached to the cable drum 78 and gear 80 by means of pin 108, while the opposite end of the spring is attached to the support plate 66 by means of a stationary sleeve or cylindrical member 110. After the cable drum has been rotated through a predetermined angle, if the pawl 100 is then disengaged from the ratchet 72, the spring 106 will cause reverse rotation of the cable drum. The rate at which the cable drum rotates in the opposite direction is determined by the resistance offered 20 by the wind vane 96. Inasmuch as the forward rotation of the cable drum is relatively slow when the pawl 100 is engaged with the ratchet 72, the wind vane 96 does not offer any appreciable resistance. The return rotation of the cable drum, 25 however, is relatively rapid and the wind vane 96 prevents the cable drum from being returned to an initial position too rapidly. Since the return rotation of the cable drum may be stopped relatively abruptly, it is desirable to interpose a flexible or shock coupling between the wind vane 96 and the gear 80. This is the purpose 30 of the coiled coupling spring 98, since the one-way clutch action of the spring coupling permits relative motion between the gear 86 and the shaft 84 in one direction, thus allowing the wind vane 96 to rotate after the return rotation of the cable drum 78 has been abruptly stopped. Energy 35 stored in the wind vane 96 will then be dissipated by friction between the spring 98 and the shaft 84 without interposing any undue mechanical stresses in the mechanism.

The cable drum 78 is provided for the purpose of moving the scanner head longitudinally with respect to the scanning drum 20. Rotation of the cable drum 78 imparts motion to the scanner head 10 by means of a cable arrangement shown in the various figures. The complete relationship of the cable to the scanner head is best shown in Figure 6. In Figure 6, one end of the cable 112 is shown connected directly to a bracket 114 attached to the scanner head 10, the cable then being wound several turns about the cable drum 78. The other end of the cable then passes about idler pulleys 116 and 118, and the opposite end of the cable is connected to the same bracket 114 by means of a tensioning spring 120.

When the pawl 100 is in engagement with the ratchet 72, as stated above, the cable drum will be rotated in the direction indicated by the arrows in the various figures. This direction of ro-

tation causes a movement of the scanner head 10 in a direction from the clutch end of the scanning drum toward the tail stock end of the scanning drum. This direction of movement of the scanner head is relatively slow compared to the rotational speed of the scanning drum, and the relative speeds of the scanner head and the rotation of the scanning drum determine the number of lines scanned per inch of the copy. After the desired length has been scanned along the scanning drum, provision is made for automatically disengaging the pawl 100 from the ratchet 72 in order that the scanner head may be returned to its initial starting position.

Disengagement of the pawl 100 from the ratchet 72 is accomplished by the trip finger 122 (see Figure 2). The position of the trip finger may be adjusted to vary the length of travel of the scanner head, and when the cable drum is rotated sufficiently, the pawl 100 is caused to engage the end of the trip finger 122 (see Figure 2) with the result that the pawl 100 is rotated about its pivot point 102 to disengage the pawl 100 from the ratchet wheel 72. As soon as these elements are disengaged, no further driving action is provided and the spring 106 causes reverse rotation of the cable drum with a return of the scanner head to an initial starting position. The trip finger 122 is securely attached to a gear 124, which is rotationally supported on the vertical shaft 58. The gear 124 meshes with a gear 126, which is mounted on one end of shaft 128. The shaft 128 is supported by the top support plate 68, and extends therethrough in order that a control knob 130 may be attached to the opposite end of the shaft 128. The control knob 130 is naturally nonrotationally secured to the shaft 128 by means of set screws or other appropriate means. The shaft 128 also carries a gear 132, which is arranged to cooperate with a non-rotating gear 134. This latter gear acts as a locking device, and is attached to the upper support plate 68 by means of a pin 136. Inasmuch as the gear 134 is not permitted to rotate, and since the gear 132 is secured to the shaft 128, it is impossible to alter the position of the trip finger 122 without disengaging gears 132 and 134. These gears may be disengaged, however, by shifting the shaft 128 longitudinally a small amount by depressing the control knob 130, and when the gears 132 and 134 are disengaged, the position of the trip finger 122 may be rotated and altered through the action of the cooperating gears 124 and 126. Inasmuch as the trip finger 122 causes disengagement of the pawl 100 from the ratchet 72, the position of the trip finger 122, therefore, controls the length of travel of the scanner head 10 with respect to the scanning drum 20, in accordance with the variation in the length of copy to be scanned. The knob 130 may, therefore, be calibrated in inches corresponding to the length of the copy positioned on the scanning drum 20. After the trip finger 122 has been moved to the desired position as determined by the length of the material to be scanned, the knob 130 is then released and, by reason of a spring (not shown), the shaft 128 is moved longitudinally upwardly to re-engage gear 132 with stationary gear 134 to prevent any further movement of the trip finger 122. This is necessary, as will be appreciated, in view of the fact that some considerable pressure is required to cause disengagement of the pawl 100 from the ratchet 72, and in the absence of some positive restraining means, the pressure of the pawl against the trip finger might 75

cause a change in the position of the trip finger, which would result in altering the length of travel of the scanner head.

After the trip finger 122 has caused disengagement of the pawl 100 from the ratchet 72, the cable drum 78 is then permitted to return to a normal position, and this rotation is impeded by the air governor or wind vane 96. The reverse rotation of drum 78 returns the scanner head to its initial starting point. The scanner head 10, as well as the cable drum 78, will then remain in this position until the pawl 100 is again engaged with the ratchet 72. The mechanism for causing re-engagement of the pawl and ratchet drive mechanism includes also a construction for counting the number of scanning operations, as well as a construction for preventing re-engagement of the pawl 100 with the ratchet 72 after a desired and selected number of scanning operations has been completed.

The upper support plate 68 has positioned thereon a rotatable shaft 136, the shaft being supported by an appropriate bearing structure 138 which will prevent axial movement of the shaft 136. At one end of the shaft is positioned a knob 140, the knob being attached to the shaft by means of set screws or other appropriate securing means. The shaft also carries a ratchet 142 and a notched cam 144. Both of these elements are secured to the shaft 136 and rotate therewith. A pawl 146 (see Figure 3) is arranged to cooperate with the ratchet wheel 142, and the pawl is attached to one end of an operating lever 148. The opposite end of the operating lever is secured to a vertical shaft 150, so that when the shaft is rotated through a small arc, the operating arm 148 will cause movement of pawl 146 to advance the rotation of the ratchet wheel 142 by one step. The rod 150 extends through both the upper and lower support plates 68 and 66 respectively, and to the lower end of the rod 150 is attached an operating arm 152 (see Figures 2 and 4). This arm is positioned to extend in the direction of the cable drum 78 so that it will lie in position to be engaged by the pawl 100 when the drum is returned to its initial starting position. A spring 154 is associated with the pawl 146, one end of the spring being attached to the pawl and the opposite end of the spring being attached to a post 156 secured to the upper support plate 68.

As stated above, a cam wheel 144 is also secured to the shaft 136 and rotates with the ratchet wheel 142. The notched cam 144 is provided with a single notch 158 (see Figure 3) for cooperation with a slide bar 160. The slide bar is retained in position by means of a pair of studs or posts 162, the posts being secured to the upper support plate 68. The bar is provided with an elongated slot in order that the bar may move in a radial direction with respect to the notched cam 144. One end of the bar cooperates with the notched cam 144, and the opposite end of the bar cooperates with an extension 164 on the lever 148. The length of the bar is so chosen that when the rod 150 is rotated clockwise (as viewed in Figure 3) the pawl 146 will advance the ratchet wheel 142 one step, but further rotation of the shaft 150 and of the lever 148 will be prevented by reason of the fact that the extension 164 will contact the bar 160, which in turn will be brought into contact with the surface or periphery of the notched cam wheel 144. Further rotation of the rod 150 and the lever 148 will, therefore, be prevented.

The rod 150 is rotated in a clockwise direction each time the pawl 100 engages the operating arm 152, when the cable drum is permitted to return to its initial position by reason of the action of the spring 106. The force of the spring 106 is sufficient to rotate the rod 150, and to thereby advance the cam wheel 142 one step. Since the knob 140 is attached to the shaft 138, which carries the ratchet wheel 142, the knob may then be graduated in numbers of scanning cycles or complete scanning operations, since at the conclusion of each scanning operation, the knob 140 is rotated an amount equivalent to one ratchet tooth.

After the ratchet wheel 142 and the knob 140 have been rotated one step, the slide bar 160 then prevents any further rotation and the inertia of the cable drum 78, as well as the force of the spring 106, exert sufficient back pressure on the pawl 100 to cause it to be engaged with the ratchet 72. As soon as the pawl 100 is forced into engagement with the ratchet 72, rotation of the shaft 58 and the ratchet 72 then causes the cable drum 78 to be rotated in a forward direction to thereby move the scanner head in a scanning direction, and to initiate the next succeeding scanning operation. This scanning operation continues, as explained above, until the pawl 100 comes into engagement with the trip finger 122, at which time the pawl is disengaged from the ratchet wheel 72 and the mechanism is returned to its starting position. Simultaneously with the return of the mechanism to the starting position, the knob 140 is moved an amount equivalent to one ratchet step on the ratchet wheel 142, and the pawl 100 is again re-engaged with the ratchet 72.

If, however, the last desired scanning operation has been performed when the cable drum 78 is returned to its initial starting position and the pawl 100 is caused to engage the operating arm 152, the shaft 150 will be rotated to advance the ratchet wheel 142 one step, which will then bring the notch 158 in alignment with the slide bar 160 so that the slide bar may engage the notch 158 and thereby permit the rod 150 and the lever 148 to rotate through more than the usual angle. This increased rotation of the rod 150 likewise permits the operating arm 152 to be rotated by the pawl 100 a corresponding amount, and by reason of this increased permissible rotation of the rod 150, the pawl 100 is not re-engaged with the ratchet 72. The inertia of the cable drum 78 and the force of the spring 106 instead of being absorbed by the operating arm 152 to cause engagement of the pawl 100 with the ratchet 72, is instead absorbed by a stop member 168 secured to the lower support plate 66. A cooperating post 168 is secured to the cable drum 78 in the vicinity of the region where the pawl 100 is secured. Therefore, when the last desired scanning operation has been performed, the inertia of the mechanism, together with the force of the spring 106 is overcome by cooperation of the pin 168 with the stop 166 so that the pawl 100 is not forced into engagement with the ratchet 72, with the result that the scanning mechanism remains stationary even though the ratchet 72 continues to rotate.

The upper end of the rod 150 is provided with an operating knob 170 for initially engaging the pawl 100 with the ratchet 72. After the last desired copy has been scanned, as explained above, and the shaft 150 is permitted to rotate through more than the usual angle, resulting in a failure 75

to re-engage the pawl 100 with the ratchet 72, the scanning drum 20 is then normally removed and a new copy attached thereto. After the drum has been installed in the machine and brought up to proper operating speed and phase relationship with respect to the recording drum, the mechanism is then in condition to operate, which naturally requires an engagement of the pawl 100 with the ratchet 72. This is accomplished by merely setting the knob 140 to the desired number of copies by rotation in a counter-clockwise direction. This rotation shifts the slide bar 160 and simultaneously rotates shaft 150 in a counter-clockwise direction, with the result that the operating arm 152 causes engagement of the pawl 100 with the ratchet 72. If only a single facsimile copy is desired (i. e., one scanning cycle) the pawl 100 may be engaged with the ratchet 72 by manually rotating the operating knob 170 and the shaft 150 in a counter-clockwise direction (see Figures 3 and 4) which causes a corresponding rotation of the operating arm 152, with the result that the pawl 100 is caused to engage the ratchet 72 by reason of the motion of the operating arm 152.

As soon as the pawl 100 is engaged with the ratchet 72, the scanning operation begins. The knob 140 may then be set at the desired number of copies (if it has not been previously so set) by rotating the knob counter-clockwise through 360 degrees less an amount equivalent to the amount that the knob will be rotated through the action of the pawl 148 when the desired number of copies has been scanned. Naturally, the knob 140 cannot be rotated in a clockwise direction at any time because of the action of the spring 154 which retains the pawl 148 in engagement with the ratchet wheel 142, the spring 154 being also strong enough to likewise rotate the shaft 150 to a normal position counter-clockwise, so that it may be rotated in a clockwise direction by the operating arm 152 when the pawl 100 engages the operating arm.

The scanning operation will then continue until the desired number of scanning operations has been performed, and until the desired number of copies has been made, at which time the slide bar 160 is again permitted to enter the notch 158 in the notched cam 144 to stop any further action by preventing re-engagement of the pawl 100 with the ratchet 72.

The operating knob 170 may also be used to manually advance the notched cam 144, the ratchet wheel 142 and the knob 140 by individual steps, should it subsequently be desired to reduce the number of copies to be made by the duplicator. A reduction in the number of copies could also be made by a slight counter-clockwise rotation of the knob 140, or if an increased number of copies were desired, the knob 140 could then be rotated through less than 360 degrees to thereby require an increased number of scanning operations to bring the notch 158 into alignment with the slide bar 160.

In order that the scanner head 10 may be conveniently moved longitudinally with respect to the scanning drum 20, a stationary rod 170 is positioned on the scanner parallel to the scanning drum. This rod may be supported by the scanner proper by means of a plurality of screws or posts 172, best shown in Figure 7. These posts are preferably of a smaller diameter than the rod 170 so that a cooperating block 174 associated with the scanner head 10 may surround the rod 170 by more than 180

degrees to thereby prevent any possibility of the scanner head being lifted from engagement with the rod. This assures that the front end of the scanner head 10, i. e., the end most adjacent the scanning drum, will not move in a direction other than along a line parallel to the axis of the scanning drum 20. The back edge of the scanner head 10, i. e., the end adjacent the light source 14, is provided with a flange member 176, to which is attached a roller 178. The roller is arranged to cooperate with a track 180 to support the back end of the scanner head, and to permit the scanner to be moved longitudinally with respect to the scanning drum.

The operation of the scanner will now be briefly described.

After the scanning drum 20 has been loaded with a document or paper of which a number of duplicate copies are desired, the scanning drum is then placed in the machine and is brought up to speed by operation of the clutch 22, and is properly phased with respect to the printing drum 26 by reason of the action of the special clutch 22 and tail stock assembly 24, shown and described in detail in the above referred to Artzt application. Inasmuch as the motor for driving the entire mechanism is permitted to continuously operate, the gear 56 and the ratchet 72 continuously rotate in a direction indicated by the arrows in the various figures.

In order to begin the scanning operation, and in order to advance the scanner head 10 along the length of the scanning drum, the pawl 100 is engaged with the ratchet 72 by a counter-clockwise rotation of knob 140 or knob 170. Rotation of either of these knobs causes the operating arm 152 to toggle the pawl into engagement with the ratchet. The cable drum 78 is then rotated in the direction indicated by the arrows at a relatively slow rate, to cause the scanner head to move longitudinally with respect to the scanning drum, in order to produce the scanning operation. After the cable drum 78 has rotated through a predetermined angle, the pawl 100 then engages the trip finger 122, with the result that the pawl 100 is disengaged from the ratchet 72. The position of the trip finger 122 may be changed in accordance with the length of the particular document or material being scanned.

Disengagement of the pawl 100 from the ratchet 72 frees the cable drum from the ratchet 72, with the result that the spring 106 which was stressed during the scanning operation, causes reverse rotation of the cable drum. This reverse rotation, together with the return stroke of the scanner head, is prevented from returning too rapidly by action of the wind vane governor 96. When the cable drum 78 has returned to its initial starting position, the pawl 100 engages the operating arm 152, with the result that the shaft 150 is rotated an amount sufficient to advance the ratchet wheel 142 and the knob 140 by one step. Rotation of the rod 150 beyond such an amount is prevented by the action of the slide bar 160, and its cooperation with the peripheral edge of the notched cam disc 142. The fact that the rod 150 is only permitted to rotate through a predetermined angle causes the operating arm 152 to exert sufficient back pressure on the pawl 100 to re-engage the pawl with the ratchet wheel 72. This re-engagement then causes the cable drum 78 to rotate in a forward direction to begin the second scanning cycle.

After the desired number of scanning opera-

tions has been performed, the slide bar 160 will then be permitted to drop into the notch 158 in the notched cam wheel 144, with the result that the arm 152 and the rod 150 will be permitted to rotate through more than the usual angle. The back pressure normally exerted by the operating arm 152 will then be absent, and the inertia of the mechanism will be absorbed by the stop pin 166 rather than the operating arm 152. Further rotation of the operating arm 152 by reason of the presence of the notch 158 prevents re-engagement of the pawl 100 with the ratchet wheel 72, and the scanning operation is discontinued even though the driving motor, the scanning drum 20 and the printing drum 26 continue to rotate.

If it is desired to change the distance scanned along the scanning drum 20 by reason of a change in the length of the document scanned, it is only necessary to depress the knob 130 to disengage gear 132 from stationary gear 134, so that the shaft 120 may be rotated to thereby rotate the trip finger 122 through action of gears 124 and 126. The trip finger 122 may thereby be positioned at any location around the periphery of the cable drum, so that the entire length of the scanning drum may be scanned or any smaller part thereof. Naturally, the scanning operation always begins at the clutch end of the scanning drum, so that when the copy is positioned on the scanning drum, any part of the scanning drum not covered by the document should be left wholly at the tail stock end of the scanning drum.

From the above it may be seen that the present invention provides various desirable features in a facsimile scanner or transmitter, the features being particularly desirable in a facsimile duplicator. By means of the present invention it is possible to perform a series of successive scanning operations of a single document without any attention on the part of the operator whatsoever, after the scanning operation has been begun and after the machine has been set to perform the desired number of scanning operations.

Furthermore, it will be appreciated that the scanning operations will be discontinued as soon as the desired number of scanning cycles has been completed. The invention also provides mechanism whereby it is unnecessary to scan the entire length of the scanning drum during each scanning cycle, since in many instances the entire drum would not be covered by the particular material being scanned. Since it would be a waste of time to scan the entire length of the scanning drum, provision has been made in the present invention whereby the scanner head 10 may be returned to its initial scanning position immediately after any desired distance along the scanning drum has been scanned. This scanning distance is immediately and readily adjustable, and may be conveniently altered to suit any particular circumstances.

Although the present invention has been described in considerable detail, it is to be understood that various alterations and modifications of the present invention may become apparent to those skilled in the art, and it is desirable that any and all such modifications and alterations be considered within the purview of the present invention except as limited by the hereinafter appended claims.

Having now described my invention, what I claim is:

1. A facsimile transmitter comprising a scanning drum and a scanner head, means for rotat-

ing the scanning drum at a predetermined speed, means for moving the scanner head in one direction at a relatively slow rate of speed along the scanning drum in a direction parallel to the axis of rotation of the scanning drum thereby to scan a predetermined distance along the drum, means for moving the scanner head in the opposite direction at a relatively fast rate of speed after the scanner head has moved a predetermined distance in said one direction, adjustable mechanical means for determining the distance scanned along the drum, means for repeating the scanning operation a predetermined adjustable number of times, and means for discontinuing the scanning operation after the predetermined number of scanning operations have been performed.

2. A facsimile transmitter comprising a scanning drum and a scanner head, means for rotating the scanning drum at a predetermined speed, means for moving the scanner head in one direction at a relatively slow rate of speed along the scanning drum in a direction parallel to the axis of rotation of the scanning drum thereby to scan a predetermined distance along the drum, means for moving the scanner head in the opposite direction at a relatively fast rate of speed after the scanner head has moved a predetermined distance in said one direction, means for repeating the scanning operation a predetermined adjustable number of times, and means for discontinuing the scanning operation after the predetermined number of scanning operations have been performed.

3. A facsimile transmitter comprising a scanning drum and a scanner head, means for rotating the scanning drum at a substantially constant speed, means for moving the scanner head in a forward direction at a relatively slow rate of speed proportional to the speed of rotation of the scanning drum, the direction of movement of the scanner head being along the scanning drum and in a direction parallel to the axis of rotation of the scanning drum to thereby scan a predetermined distance along the drum, adjustable mechanical means for determining the distance scanned along the drum, means responsive to the action of said adjustable mechanical means for moving the scanner head in the reverse direction at a relatively fast rate of speed after the scanner head has moved the predetermined distance in said forward direction, means for repeating the forward and reverse movements of the scanner head a predetermined adjustable number of times to repeat the scanning operation, and means for discontinuing the scanning operation after the predetermined number of scanning operations have been performed.

4. A facsimile transmitter comprising a scanning drum and a scanner head, means for rotating the scanning drum at a predetermined substantially constant speed, means for moving the scanner head in one direction at a substantially constant relatively slow rate of speed along the scanning drum in a direction parallel to the axis of rotation of the scanning drum to thereby scan a predetermined distance along the drum, means for moving the scanner head in the opposite direction at a relatively fast rate of speed after the scanner head has moved a predetermined distance in said one direction, adjustable mechanical means for determining the distance scanned along the drum, and means for repeating the scanning operation a predetermined adjustable number of times.

5. A facsimile transmitter comprising a scanning drum and a scanner head, means for rotating the scanning drum at a predetermined speed, means for moving the scanner head in one direction at a relatively slow rate of speed commensurate with the speed of rotation of the scanning drum, the direction of movement of the scanner head being parallel to the axis of rotation of the scanning drum to thereby scan a predetermined distance along the drum, means for moving the scanner head in the opposite direction at a relatively fast rate of speed after the scanner head has moved a predetermined distance in said one direction, and adjustable mechanical means for determining the distance scanned along the drum.

6. A facsimile scanner comprising a scanning drum and a scanner head, means to continuously rotate the scanning drum at a predetermined speed, ratchet means associated with the scanning drum and rotated at a relatively slow speed by said first named means, a cable drum associated with said ratchet means, means to mechanically connect the cable drum to said continuously rotating ratchet means to thereby rotate the cable drum, means to couple the cable drum to the scanner head to cause the scanner head to move at a relatively slow rate of speed in one direction along the scanning drum in a path parallel to the axis of rotation of the scanning drum to thereby scan a predetermined distance along the drum, means to mechanically disconnect the cable drum from the ratchet means, and means associated with said cable drum for moving the scanner head in the opposite direction at a relatively fast rate of speed after the scanner head has moved a predetermined distance in said one direction.

7. Apparatus such as defined in claim 6, wherein said means to disconnect the cable drum from the ratchet means comprises a trip finger, and means for adjusting the position of the trip finger relative to the cable drum whereby various adjustable lengths may be scanned along the scanning drum.

8. A facsimile scanner comprising a scanning drum and a scanner head, motor means for rotating the scanning drum at a predetermined substantially constant speed, a ratchet wheel, means to rotate said ratchet wheel at a relatively slow speed by said motor means, a cable drum and pawl positioned to cooperate with said ratchet wheel, means including said pawl for mechanically connecting the cable drum to said rotating ratchet wheel to thereby rotate the cable drum, means for coupling the cable drum to the scanner head to cause the scanner head to move at a relatively slow rate of speed in one direction along the scanning drum in a path parallel to the axis of rotation of the scanning drum to thereby scan a predetermined distance along the drum, means to operate said pawl to mechanically disconnect the cable drum from the ratchet wheel, and means associated with said cable drum for moving the scanner head in the opposite direction at a relatively fast rate of speed after the scanner head has moved a predetermined distance in said one direction.

9. Apparatus such as defined in claim 8, wherein said means to operate said pawl to mechanically disconnect the cable drum from the ratchet wheel comprises a trip finger, and means to adjust the position of the trip finger relative to the cable drum whereby the pawl may be operated

after any desired distance has been scanned along the scanning drum.

10. A facsimile scanner comprising a scanning drum and a scanner head, motor means for rotating the scanning drum at a substantially constant speed, a ratchet wheel, means to continuously rotate said ratchet wheel at a relatively slow speed by said motor means, a cable drum associated with said ratchet wheel, a pawl for mechanically connecting the cable drum to said continuously rotating ratchet wheel to thereby rotate the cable drum, a cable to connect the cable drum to the scanner head to cause the scanner head to move in a forward direction at a relatively slow rate of speed along the scanning drum when the cable drum is rotated by the ratchet wheel to thereby scan a predetermined distance along the drum, means to operate the pawl to mechanically connect the cable drum to the ratchet wheel, means to operate the pawl to mechanically disconnect the cable drum from the continuously rotating ratchet wheel, and a spring means associated with said cable drum for moving the cable drum and scanner head in the reverse direction at a relatively fast rate of speed after the cable drum and ratchet wheel have been mechanically disconnected.

11. Apparatus such as defined in claim 10, wherein said means to operate the pawl to mechanically disconnect the cable drum from the ratchet wheel comprises a trip finger positioned in the path of movement of the pawl, and means to adjust the position of the trip finger relative to the path of movement of the pawl whereby any predetermined distance may be scanned along the scanning drum.

12. A facsimile scanner comprising a scanning drum and a scanner head, a clutch mechanism associated with the scanning drum, driving means for continuously rotating the clutch mechanism at a predetermined relatively high rate of speed, ratchet means mechanically connected to said driving means and continuously rotated thereby at a relatively slow rate of speed as compared to the speed of rotation of the clutch mechanism, a drum and pawl positioned to cooperate with said ratchet means, means associated with said drum and connected to the scanner head for moving the scanner head in one direction or another depending upon the direction of rotation of said drum, means for causing engagement of the pawl with the ratchet means to thereby rotate said drum in one direction to move the scanner head in a forward direction at a relatively slow rate of speed along a path parallel to the axis of rotation of the scanning drum to thereby produce a scanning operation, a trip finger positioned to cooperate with the pawl so that after said drum has been rotated through a predetermined angle by the ratchet means the pawl will engage the trip finger to mechanically disengage said drum from the rotating ratchet means, means for adjusting the position of the trip finger to alter the angle through which the drum is permitted to rotate so that different adjustable distances along the scanning drum may be scanned, spring return means associated with the cable drum for rotating said drum in the opposite direction and for returning the scanner head to an initial starting position when said drum is mechanically disengaged from the ratchet means, means for governing the rate of return of the scanner head to the initial starting position, and means to cooperate with said pawl to re-engage the drum with the ratchet means

when the scanner head has returned to its initial starting position.

13. Apparatus such as defined in claim 12, wherein said means to cooperate with said pawl to re-engage the drum with the ratchet means includes a counter mechanism for counting the number of complete scanning cycles, and means for preventing re-engagement of the drum with the ratchet means after a predetermined number of scanning cycles have been performed.

14. A facsimile scanner comprising a scanning drum and a scanner head, a clutch mechanism associated with the scanning drum, driving means for continuously rotating the clutch mechanism at a predetermined relatively high rate of speed, ratchet means mechanically connected to said driving means and continuously rotated thereby at a relatively slow rate of speed as compared to the speed of rotation of the clutch mechanism, a cable drum and pawl positioned to cooperate with said ratchet means, means associated with the cable drum and connected to the scanner head for moving the scanner head in one direction or another depending upon the direction of rotation of the cable drum, means for causing engagement of the pawl with the ratchet means to thereby rotate the cable drum and pawl in one direction to move the scanner head in a forward direction at a relatively slow rate of speed to thereby produce a scanning operation, a normally stationary trip finger positioned to cooperate with the pawl so that after the cable drum has been rotated through a predetermined angle by the ratchet means the pawl will engage the trip finger to mechanically disengage the pawl from the rotating ratchet means, means associated with the cable drum for rotating the cable drum in the opposite direction and for returning the scanner head to an initial starting point when the pawl is mechanically disengaged from the ratchet means, and means to re-engage the pawl with the ratchet means when the scanner head has returned to its initial starting point.

15. Apparatus such as defined in claim 14, wherein said means to re-engage the pawl with the ratchet means includes a counter mechanism for counting the number of complete scanning cycles, and means for preventing re-engagement of the pawl with the ratchet means after a predetermined number of scanning cycles have been performed.

16. A facsimile scanner comprising a scanning drum and a scanner head, a clutch mechanism associated with the scanning drum, motor means for continuously rotating the clutch mechanism at a predetermined relatively high rate of speed, a ratchet wheel mechanically connected to said driving means and rotated at a relatively slow rate of speed as compared to the speed of rotation of the clutch mechanism, a cable drum and pawl arranged to cooperate with said ratchet wheel, means associated with the cable drum and connected to the scanner head for moving the scanner head in one direction or another depending upon the direction of rotation of the cable drum, means to engage the pawl with the ratchet wheel to thereby rotate the cable drum in one direction to move the scanner head in a forward direction at a relatively slow rate of speed to thereby perform a scanning operation, a trip finger positioned to engage the pawl after the cable drum has rotated through a predetermined angle to disengage the pawl from the rotating ratchet wheel.

means to adjust the position of the trip finger to alter the angle through which the drum is permitted to rotate so that different adjustable distances along the scanning drum may be scanned, and means associated with the cable drum for rotating the cable drum in the opposite direction and for returning the scanner head to an initial starting point when the pawl is mechanically disengaged from the rotating ratchet wheel.

17. Apparatus such as defined in claim 16, wherein said means to engage the pawl with the ratchet wheel includes a counter mechanism for counting the number of complete scanning cycles.

18. A facsimile scanner comprising a longitudinally movable scanner head, a ratchet wheel, driving means to continuously rotate said ratchet wheel at a relatively slow rate of speed, a cable drum and pawl positioned to cooperate with said ratchet wheel, means associated with the cable drum and connected to the scanner head for moving the scanner head in one direction or another depending upon the direction of rotation of the cable drum, means for causing engagement of the pawl with the ratchet wheel to thereby rotate the cable drum in one direction to move the scanner head in a forward direction at a relatively slow rate of speed to thereby perform a scanning operation, a trip finger positioned to contact with the pawl after the cable drum has been rotated through a predetermined angle by the ratchet wheel to mechanically disengage the pawl and cable drum from the continuously rotating ratchet wheel, means for altering the position of the trip finger to vary the angle through which the drum is permitted to rotate before the pawl contacts the trip finger so that different distances may be traversed by

the scanner head, means associated with the cable drum for rotating the cable drum in the opposite direction and for returning the scanner head to an initial starting point when the pawl and cable drum are mechanically disengaged from the rotating ratchet wheel, and means for re-engaging the pawl with the ratchet wheel when the scanner head has returned to its initial starting point.

- 10 19. Apparatus such as defined in claim 18, wherein said means for re-engaging the pawl with the ratchet wheel includes a counter mechanism for counting the number of complete scanning operations, and means to prevent re-engagement of the pawl with the ratchet wheel after a predetermined number of scanning operations have been performed.
- 20 20. A facsimile scanner comprising a scanner head, a ratchet wheel, means to continuously rotate the ratchet wheel at a relatively slow speed, a cable drum and pawl associated with said ratchet wheel, means including said pawl for mechanically connecting the cable drum to said continuously rotating ratchet wheel to thereby rotate the cable drum, means for coupling the cable drum to the scanner head to cause the scanner head to move longitudinally in one direction at a relatively slow rate of speed to thereby perform a scanning operation, means to mechanically disconnect the pawl and cable drum from the ratchet wheel after the scanner head has moved a predetermined distance in said one direction, and means associated with said cable drum for moving the scanner head in the opposite direction at a relatively fast rate of speed after the pawl and cable drum have been disconnected from the ratchet wheel.

ALBERT BLAIN.
